CLAIM

The ornamental design for a palmless glove, as shown and described.

DESCRIPTION

FIG. 1 is a back elevation view of an ornamental design for a palmless glove;

FIG. 2 is a front elevation view thereof;

FIG. 3 is a bottom elevation view thereof;

FIG. 4 is a top elevation view thereof;

FIG. 5 is a right side elevation view thereof; and,

FIG. 6 is a left side elevation view thereof.

The broken lines showing a hand are for purposes of illustrating environmental structure and form no part of the claimed design. The symbolic break lines in the cuff represent a boundary between claimed and unclaimed subject matter and form no part of the claimed design. The appearance of any portion of the palmless glove between the break lines forms no part of the claimed design. It is understood that while a left-handed palmless glove is illustrated in the figures, the right-handed palmless glove is a mirror image thereof.
